UNITED STATES PATENT OFFICE.

LOUDOUN CAMPBELL, OF BALLSTON, VIRGINIA.

CAR DOOR AND MEANS FOR MOUNTING AND OPERATING THE SAME.

Application filed February 7, 1925. Serial No. 7,531.

This invention relates to car doors and means for mounting and operating the same. The purposes and advantages of the invention will be better appreciated if some of the existing conditions with respect to devices of this sort are understood.

The railroads of this country suffer enormous financial loss, annually, because of the damage done to car doors, by the receiver 10 of freight, in trying to get said doors open. It is frequently the case that a car door will resist the combined efforts of four or five men to open it and then crow bars, picks, or anything else that happens to be 15 handy, are used to pry the door open, the points of these instruments being struck into the body of the car to get the necessary purchase to initially start the movement of the door. This not only directly damages 20 the car sides and sills but, in addition, by permitting the entry of water sets up rotting of these parts which ultimately result in large repair bills.

Some of the causes which render it so 25 difficult to get the doors of freight cars open are as follows:

A. Since the height of the car is such that a man trying to push the door open can reach only the lower portion of the door, it 30 follows that his attempt to push the door will tend to "cock" it, in its guides and thus cause a binding of the same.

B. The guides or tracks frequently get 35 out of line either as a result of accidents or as a result of "weaving" of the car when in motion, and

C. The freight in the car sometimes shifts 40 in transit and moves against the inside of the door in such manner as to engage the battens upon the inner face of the door and thus resist opening movement of the door.

In order to obviate the foregoing difficulties the present invention contemplates the 45 provision of a guide means connected to but spaced from the door proper and guiding it centrally, in such way that it cannot "cock" with respect to the mountings.

The invention further contemplates the 50 provision of a lever arranged to compound the force exerted by a person tending to open the door in such manner that one man can exert as much pressure upon the door

as several men could exert in a straight push.

The invention further contemplates the 55 provision of a door provided with batten of a wedge shape so that movement of the door will tend to throw any freight which may have moved toward the door, away from said door.

The invention further contemplates the 60 provision of a plurality of somewhat closely spaced rollers constituting the support for the lower edge of the door and the mountings of which serve as spacing elements for the lower guide rail and aid in preventing 65 bending thereof if a truck or other vehicle is backed thereagainst.

Further objects and advantages of the invention will be set forth in the detailed description which follows:

In the accompanying drawings:

Figure 1 is a side elevation of a portion 70 of a car having the invention applied thereto.

Figure 2 is a fragmentary vertical sectional view through the car body and the door of the present invention.

Figure 3 is a front elevation of a portion 75 of the door illustrating the operating lever for the same.

Figure 4 is a horizontal sectional view 80 through the door illustrating one of the battens hereinafter described.

Figure 5 is a sectional view illustrating 85 the mounting of the rollers upon which the lower edge of the door is supported, and

Figure 6 is a detail view illustrating a modification hereinafter described.

Like numerals designate corresponding 90 parts in all of the figures of the drawing:

Referring to the drawing, 5^a, designates the sill of the car, 6, the side walls, 7 the floor and 8 the top. The door 9 has its upper edge guided in an angle rail 10 and its lower edge supported upon a series of rollers 11. See Figures 1 and 5. The lower edge of the door is held against outward movement by guide rail 12 and this guide rail is spaced from the sill of the car by inner sleeves 13 which constitute the journals for the rollers 11 and which are in turn supported by bolts 14 which pass through the sill of the car. Thus it will be 95 100

seen that the sleeves 13 constitute spacing elements to hold the rails 12 a given distance from the sill of the car. This prevents binding of the rollers 11 and braces the rail 12 to resist bending if a truck or wagon should be backed thereagainst in loading or unloading the car.

To prevent the door 9 from cocking in the guides, constituted by the rails 10 and 12 and the rollers 11, I provide an elongated flat bar 15, which at a point outside of the range of travel of the door, passes through a suitable guide, which in the present embodiment of the invention takes the form 18 of a pair of idle rollers 16 which are mounted upon the inner face of a vertically disposed strap 17. Thus it is clear that the door cannot cock in either direction, but must travel in a straight line as guided by 20 the strap 15 and the rollers 16. The strap 15, which is secured to the door 9 in any desired manner, as for example by bolts, at 18, is provided with a plurality of outwardly projecting pins 19, which are adapted to be 25 engaged by the nose 20, which constitutes the short arm of a lever 21. This lever is provided with a slot 22 and is pivoted upon a stud 23 which projects from the inner face of a vertically extending strap 24 that is 30 supported from the car body. The dotted lines in Figure 3 indicate the position that the nose of the lever occupies after the lever has been swung to move the door, one step, in a direction to open it. After this has 35 been done the lever is rocked to the full line position, illustrated in Figure 3, and swung upon its stud, and then forced upwardly to cause its nose to engage the next pin 19 to the left, so that a further swinging movement of the long arm 21 of the lever will result in opening the door another step. Since this long movement of the arm 21 will result in opening the door only a short distance it follows that one man may 40 exert as much pressure on the door at a given moment as several men could do, with a straight push. Referring to Figure 3, 9^a designates the boards constituting the body of the door and 9^b designates a batten 45 tending along its inner face. From this figure it will be observed that this batten has its face beveled in opposite directions so that if any freight should shift during the movement of the car, over toward the inner face of the door, the operation of the door under the influence of the lever 21, in conjunction with the wedge shape of the batten, will result in thrusting said freight 50 away from the inner face of the door. In Figure 6, I have illustrated a construction involving the use of a rack arm 30 which is set into the face of the sill 5^a. By engaging a crow-bar or other pry with the teeth of the rack bar, the door may be pried open. However, the construction illustrated

in Figures 1 and 2 is preferred since the latter provides means for preventing the door from cocking.

It is to be understood that the invention is not limited to the precise construction set forth, for manifestly many ways will readily suggest themselves for guiding the door to prevent cocking and for compounding the leverage which the operator may exert in his effort to open the door. It is therefore to be understood that the invention is not limited to the precise construction set forth but that it includes within its purview whatever changes fairly come within the terms or the spirit of the appended claims.

Having described my invention what I claim is:

1. The combination with a freight car door of means for mounting the same for slideable, horizontal movement, at its upper and lower edges, a plurality of outwardly projecting elements disposed in a row across the width of said door; a fixed support carried by the car body and lying outwardly of the plane of travel of the door, a lever mounted for bodily endwise movement and for swinging movement upon said support and comprising a long arm and a short arm, the endwise movement of the lever upon its support bringing the short arm of the lever into position for engagement with the outwardly projecting elements of the door, the swinging movement of the lever being in a plane substantially parallel to the outer face of the door.

2. A structure as recited in claim 1, in combination with a bar carried by the door and projecting a material distance beyond the door in the line of travel thereof, and guide members between which said bar travels, said members resisting the tendency of the door to cock under the action of the said lever as said lever is actuated to open the said door.

3. The combination with a freight car door of means for mounting the same for sliding movement, a strap extending across the face of said door and projecting rearwardly therebeyond, guide means engaging said strap beyond the plane of travel of the door, a fixed member carried by the car body and lying in front of the door, a lever mounted upon said member and having slotted engagement therewith and a plurality of outwardly projecting elements carried by the door and adapted to be engaged by said lever.

4. The combination with a freight car door of means for mounting the same for slideable movement at its upper and lower edge, a bar extending horizontally across the face of said door and to a point materially beyond the rear edge thereof, a plurality of pins carried by said bar and projecting beyond the face thereof, a pair of

guide rollers between which the rear end of said bar travels, a fixed, vertically disposed element lying outwardly of the car door, a lever comprising a long arm and a relatively short arm and a pin and slot connection between the lever and said fixed element constituting the pivot point of said lever and

adapting the short arm of the lever to be shifted bodily into and out of engagement with the pins of said bar.

In testimony whereof I hereunto affix my signature.

10

LOUDOUN CAMPBELL.
